J. JOHNSTON

LIGHT FOR CHRISTMAS TREES AND THE LIKE

Filed Jan. 28, 1924

UNITED STATES PATENT OFFICE.

JOHN JOHNSTON, OF CHICAGO, ILLINOIS.

LIGHT FOR CHRISTMAS TREES AND THE LIKE.

Application filed January 28, 1924. Serial No. 688,952.

To all whom it may concern:

Be it known that I, JOHN JOHNSTON, a citizen of the United States, residing at Chicago, in the county of Cook and State of Illinois, have invented certain new and useful Improvements in Lights for Christmas Trees and the like, of which the following is a specification.

This invention relates to improvements in lights for Christmas trees and the like, and one of the objects of the invention is to arrange the lights in a manner to produce a design or ornament adapted to be secured preferably to the top of the tree or to the end of a branch of the tree for the purpose of illuminating as well as ornamenting the tree.

A further object is to provide an improved device of this character having connected therewith through the medium of extended conductors a plurality of additional lamps that may be arranged or festooned about the tree, the conductors having connected therewith a plug, by means of which the device may be connected with a socket supplied with current from any suitable source.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a view in elevation of a light and ornament of this character constructed in accordance with the principles of this invention and showing the same as connected with the tip of one of the branches of a tree.

Figure 2 is a vertical sectional view taken on line 2-2, Figure 1, and with parts omitted.

Figure 3 is a horizontal sectional view taken on line 3-3, Figure 1.

Figure 4 is a view similar to Figure 1, partly broken away and partly in section of a modified form of the invention.

In the form of the invention as shown in Figure 1, there are provided spaced clamp-

ing members 10-11, which may be constructed of any suitable material and may be of any desired size and configuration, but they are preferably shaped so as to form opposed recessed portions 12-13, and which portions are preferably radially disposed so that when the members are assembled with respect to each other, the opposed portions 12 and 13 will be adapted to receive sockets 14.

The members 10 and 11 are preferably adapted to be secured together by means of a clamping member or bolt 15 which preferably passes through the center of the members and the fastening device 15 also serves as a means for holding the sockets 14 in position.

If desired the sockets may be provided with recesses 16 adapted to receive projections 17 formed on the members 12 and 13.

The sockets 14 are preferably constructed of any suitable insulating material and are each provided with a metal collar or sleeve 18 having internal screw threads adapted to receive the metal threaded extremity 19 of a lamp 20. To this sleeve 18 is connected a conductor 21 and another conductor 22 terminates in a contact 23 within the socket 14 so that when the lamp 20 is placed in the socket the contact 24 will engage the contact 23 as is usual in lamps of this character.

The members 12 and 13 are so shaped that any desired number of these sockets 14 may be secured together so as to produce an ornamental design and so that the lamps 20, which are connected with the respective sockets will be arranged in any desired manner.

These lamps 20 are preferably connected in series and current is supplied through the medium of conductor wires or cords 25.

Included in the conductor wires 25 may be arranged any desired number of additional sockets 26 to receive lamps 27 and the sockets are preferably connected in series, the conductors being of such a length that when the ornament is secured to a branch of the tree, the lights 27 may be arranged or festooned about the body of the tree or branches. A plug 28 is connected to the conductors 25 and this plug is adapted to be inserted in a suitable socket and to which lat-

ter socket current is supplied from any suitable source, such as a wall socket or the like. With this improved arrangement it will be manifest that the ornament may be arranged 5 in any position upon the tree while the lights 27 may be arranged as desired.

- Any suitable means may be provided for supporting the ornament. A simple and efficient means embodies spaced clamping 10 members 39-30, which may be of any desired size and configuration and constructed of any suitable material. The ends of these clamping members 29-30 are respectively secured by suitable fastening means 31-32 15 to the members 12 and 13, so that the end of a branch 33 of the tree may pass between the members 29-30, after which the supporting members may be secured in clamping relation to the branch in any desired or suitable manner, preferably by means of some 20 suitable flexible fastening device such as a wire 34 or the like, adapted to be wound about the members 29-30 and also the branch 33.
- Obviously the entire device will be constructed of some suitable light material which may be supported in proper position by the end of the branch or tree.

In the form of the invention shown in 30 Figure 4, there is provided an integral construction, in which the body is preferably in the form of an annular member 35, having sockets 36 connected therewith, any number of which sockets may be provided according to the design which it is desired to produce. Each of these sockets is provided with a metal sleeve 37, having threads with which the threaded extremity 38 of the lamp 39 will engage. Conductors 40 are provided 35 which co-operate with conductors 41 and connect the sockets 36 in series, the conductor 40 being connected with a metallic sleeve 37, while the conductor 41 is connected with the contact 42 in the socket, the connecting portion of the conductors 41 between the sockets being disposed within the opening of the annular member 35.

Supporting members 43 similar to the 50 members 29-30 are connected with the member 35 for supporting the ornament upon a tree or branch. The sockets 36 are supplied with current through suitable conductors 44, and with which conductors any number of sockets similar to the sockets 26 55 may be connected in series.

This construction is adapted to be supported or secured to the branch 33 of the tree in a manner similar to the form shown in Figure 1, that is by means of a suitable 60 flexible fastening device 45, adapted to be wrapped around the members 43 and also the branch 33.

While the preferred forms of the invention have been herein shown and described 65 it is to be understood that various changes

may be made in the details of construction and in the combination and arrangement of the several parts, within the scope of the claims, without departing from the spirit 70 of this invention.

What is claimed as new is:—

1. A light for Christmas trees and the like including a plurality of light sockets secured to a fixed support, conductors connected with the said sockets, additional sockets connected with the said conductors and flexibly suspended thereby from the fixed support and being movable ad-libitum with respect to the said support, a plug to which the conductors are connected, and means for securing the said support upon a tree or the like. 75

2. As an article of manufacture a plurality of electric lamp sockets rigidly connected or secured together to produce a fixed design or ornament, additional electric lamp sockets, conductors for supplying current to the sockets, said additional sockets being flexibly supported by the conductors and movable ad-libitum with respect to the 80 first recited sockets to which the said conductors are connected. 85

3. As an article of manufacture a plurality of electric lamp sockets rigidly connected or secured together to produce a fixed design or ornament, additional electric lamp sockets, conductors for supplying current to the sockets, a plug to which the said conductors are connected, the said additional sockets being separate from the first recited sockets and being supported by the said conductors, and a standard pendant from the ornament for holding the same and for detachably securing the said design or ornament to a tree or the like. 90

4. As an article of manufacture a lighting system for trees or the like and including a plurality of electric lamps assembled and rigidly secured together in a fixed relation to form an ornament, conductors for supplying current to the lamps, additional lamps connected with the conductors and pendant from the first recited lamps, a standard pendant from the ornament for supporting it and for securing the first recited structure to a tree or support, and a plug to which the conductors are connected. 110

5. As an article of manufacture a lighting system for trees or the like including a plurality of radially arranged lamps rigidly secured together in fixed relation, conductors for supplying current to the lamps, additional lamps connected with the said conductors, said additional lamps being separate and pendant from the first recited lamps supported by the said conductors, and a plug connected with the said conductors. 120

6. As an article of manufacture a lighting system for trees or the like including a plurality of radially arranged lamps rigidly 125

secured together in fixed relation, conductors for supplying current to the lamps, additional lamps connected with the said conductors, said additional lamps being 5 separate and pendant from the first recited lamps, an electric socket plug connected to the ends of the conductors, and means for detachably securing the structure to a tree or the like and for maintaining the structure in a fixed position with respect to the tree. 10 In testimony whereof I have signed my name to this specification, on this 26th day of January, A. D. 1924.

JOHN JOHNSTON.
